UNITED STATES PATENT OFFICE.

RAYMOND GUY MOORE, OF BRIDGEPORT, CONNECTICUT, ASSIGNOR TO THE BASSICK COMPANY, OF BRIDGEPORT, CONNECTICUT, A CORPORATION OF CONNECTICUT.

DOOR LATCH.

Application filed March 20, 1923. Serial No. 626,444.

To all whom it may concern:

Be it known that I, RAYMOND G. MOORE, a citizen of the United States, and resident of Bridgeport, county of Fairfield, and State of Connecticut, have invented certain new and useful Improvements in Door Latches, of which the following is a specification.

The invention relates to door latches, and particularly to improved means for securing in position a spring used in a spring-pressed latch construction. In spring-pressed latches as previously made it has been customary to anchor or secure such springs to the plate of the casing, particularly where spiral springs are used, by extending the secured end of the spring through a slit in a stud riveted to the plate. In such a case the stud has been slit down from its upper end, the spring inserted, and the portions of the stud on opposite sides of the slit pinched together above the spring to hold the latter. The slit cannot extend down flush with the surface of the plate, ordinarily, as it will be too much weakened thereby. If, accordingly, the inner end of the slit terminates a distance from the surface of the plate, the inner end of the spring has to be raised from the surface of the plate, to extend through the slit, and that tends to tilt the spring, and makes it difficult to make the spring lie flat on the plate. To avoid this difficulty special arrangements must be made, such as forming a recess in the plate, in which the stud is mounted, occasioning further labor and expense.

The present invention overcomes the difficulties referred to and provides an effective and simple means for anchoring the springs of spring pressed latch constructions, which will do away with several manufacturing operations, and effect a considerable saving in labor and cost of installation. According to the invention I provide a clip or strap, preferably bent into inverted U-shape, slip this over the end or portion of the spring to be secured, extend the ends of the clip through an opening or openings provided for that purpose in the plate, and then bend over the ends of the clip on the opposite side of the plate, or otherwise head or enlarge them, to cause them to engage the surface of the plate and thus hold the clip and spring portion embraced thereby, in position.

The object of the invention, generally speaking, is the provision of improved devices of the character referred to above. The invention consists in the various combinations of parts and details of construction hereinafter more fully set forth in accordance with the form of the invention which now seems preferable and as is more particularly set forth in the accompanying claims.

In order that the invention may be more clearly understood attention is hereby directed to the accompanying drawings forming part of this application and illustrating one embodiment of the invention. In the drawings

Figure 1 represents a front elevation shown partly in section of a door latch construction embodying the invention;

Figure 2 is a section on an enlarged scale taken on line 2—2 of Figure 1;

Figure 3 is a plan view on an enlarged scale of the clip used for securing the spring in place before the same has been pressed to form, and

Figure 4 is a side elevation of the same after it has been pressed to form.

Referring to the drawings, a bolt 1 is indicated slidably mounted on plate 2 which may be secured to a door in the usual manner. The bolt is guided and held in place by any suitable means, such as the cover plate indicated at 3. Plate 1 is provided with a flange 4 at its forward edge through an opening in which the nose of the bolt is slidably into the projected position shown in Figure 1.

The bolt may be retracted in any usual way as by means of the hand lever indicated at 5, or by a handle operated roll back. A handle operated roll back, 6, is indicated in the drawings, oscillation of which is adapted to swing lever 5 rearwardly and cause the latter to retract the bolt, lever 5 bearing against a transverse surface 7 on the bolt. A flat spring 8 is indicated secured to plate 2 and bearing against hand lever 5 to press the same forwardly. None of the features referred to form part of the present invention.

The bolt 1 is shown as pressed forwardly towards projected position by a spiral spring 9, the outer end portion of which is shown as bearing against a transverse surface such as the rear surface of the bolt.

This spring is anchored or secured in position upon plate 2 by means of the metal clip 10.

This clip may be formed of a metal blank, 5 such as is indicated in Figure 3 at 10^a which is bent into the form of an inverted U—as shown at 10^b in Figure 4. An opening or a pair of openings are provided through plate 2 through which the legs of the clip may extend. In Figure 2 of the drawings a single 10 opening 11 is indicated.

When the device is to be assembled the spring is positioned on the face of plate 2 and the clip 10 is slipped over the inner end 15 portion of the spring which is bent to extend in a substantially straight line for a short distance approximately across the center of the spiral. The clip extending over and about the inner end portion of the spring, 20 the end portions of the legs of the clip will be extended through the opening 11 and the end portions of the legs of the clip then headed or enlarged, or bent in suitable fashion to prevent the same from slipping 25 back through opening 11. As is indicated in the drawings, the end portions 12 of the clip may simply be bent at right angles to the main portion of the clip into engagement with the surface of plate 2 opposite to that on 30 which spring 9 rests.

With such a construction the spring may be mounted in position in a very short time and in a very simple manner and will lie flat on the plate without any tendency to 35 tilt. It is obvious that the spring will be held safely and securely by the device described without any tendency for the same to work or pull out of the clip.

It should be understood that the invention 40 is not limited strictly to the details of construction described but is as broad as is indicated by the accompanying claims.

What I claim is:

1. In a door latch, the combination of a 45 plate, having an opening therethrough, a

bolt slidably mounted on said plate, means for guiding the bolt, a spiral spring having its outer end engaging against the bolt to press it toward projected position, and an inverted U-shaped clip extending over the 50 inner end portion of said spring and through said opening and having its ends bent over against the opposite side of said plate to secure said spring in position.

2. In a door latch, the combination of a 55 plate, having an opening therethrough, a latch-effecting member movably mounted on said plate, a spring on said plate pressing said member towards operated position, and a bent clip extending over and about said 60 spring and having its ends extend through said opening, said ends being provided with laterally extending portions bearing against the opposite side of said plate to secure said spring in position. 65

3. In a door latch, the combination of a 70 plate, having an opening therethrough, a latch-effecting member movably mounted on said plate, a spiral spring bearing evenly against said plate with its outer end portion 75 pressing said member towards operated position, and an inverted U-shaped clip extending over an inner portion of said spring and through said opening, the ends of said clip being provided with laterally extending portions bearing against the opposite side of said plate to secure said spring in position.

4. In a door latch, the combination of a 80 plate having an opening therethrough, a member movably mounted on said plate, a spring on said plate pressing against said member and a bent clip extending over and above said spring and having its ends extend through said opening, said ends being 85 provided with laterally extending portions bearing against the opposite side of said plate to secure said spring in position.

In testimony whereof I have signed my name to this specification.

RAYMOND GUY MOORE.
